UNITED STATES PATENT OFFICE.

JOHN H. GREENHALGH, OF WOONSOCKET, RHODE ISLAND, AND HARRY GREENHALGH,
OF BLACKSTONE, MASSACHUSETTS.

LET-OFF MECHANISM FOR LOOMS.

1,062,455.

Specification of Letters Patent. Patented May 20, 1913.

Application filed January 11, 1910. Serial No. 537,515.

To all whom it may concern:

Be it known that we, JOHN H. GREENHALGH, a citizen of the United States, residing at Woonsocket, in the county of 5 Providence and State of Rhode Island, and HARRY GREENHALGH, a citizen of the United States, and resident of Blackstone, in the county of Worcester and State of Massachusetts, have invented new and useful Improvements in Let-Off Mechanism for 10 Looms, of which the following is a specification.

This invention relates to let-off mechanism for looms, the object of the invention 15 being to provide a simple and effective type of mechanism of this character whereby a uniform tension on the warp threads from beginning to finish of the weaving operation may be secured without the necessity of operating or adjusting levers or other parts or utilizing any positive take-up action, and which is adapted to permit of a free backward movement of the warps when any amount is picked out.

25 The invention consists of the features of construction, combination and arrangement of parts hereinafter fully described and claimed, reference being had to the accompanying drawings, in which:—

30 Figure 1 is an end elevation showing the application of the invention to a loom frame. Fig. 2 is a top plan view of the let-off mechanism. Fig. 3 is a rear elevation of the drive gearing thereof. Fig. 4 is a section on the line 4—4 of Fig. 2 through the ratchet wheel member of the let-off gearing. Fig. 5 is a transverse section through the transmission gears on the plane indicated by the line 5—5 of Fig. 4. Fig. 6 is 35 an end view of the feed and tension rolls showing the direction of feed movement of the warp threads.

40 Referring to the drawings, 1 designates the frame of the loom, on which is journaled the driving shaft 2 of the let-off mechanism. This shaft is provided with a hand crank 2^a and has loosely mounted thereon a shaft or sleeve 3, provided at one end with a beveled gear 4 meshing with a main drive gear 5 on the crank shaft 6 of the loom driving mechanism. The other end of the shaft 3 carries a clutch member 7 provided with a pin or projection 8 adapted to enter an opening 9 in a clutch member 10 carried by the shaft 50 2, by which, when said clutch members are

locked together, the shaft 3 will be fixed to the shaft 2 to communicate motion thereto from the shaft 6. The clutch member 10 is feathered to rotate with and slide upon the shaft 2 toward and from the clutch 60 member 7, whereby said clutch members may be thrown into and out of engagement. Said clutch member 10 is adapted to be slidably adjusted by a shipper fork 11 movable in one direction or the other through 65 the medium of an operating lever 12.

Upon the end of the frame opposite the lever 12 open bearings 13 are provided to receive the ends of the shaft 14 of the warp beam or roll 15, which is thus mounted to 70 turn freely in said bearings to permit unwinding of the warp threads 16 therefrom. Arranged above and in advance of the warp roll are guide and tension rolls 17 and 18, the roll 17 being smaller than the roll 18, 75 and disposed in advance of and at a suitable elevation above the lower portion of the periphery thereof. The threads 16, in their feeding operation, are drawn, under the pull of the take-up rollers and beating-in mechanism, from the roll 15 upwardly and rearwardly around the roll 17 and thence rearwardly under and upwardly over the surface of the roll 18, by which arrangement of the 80 two rolls 17 and 18 bights or loops are formed in the threads as they pass therearound, so that an effective feed action is secured, while at the same time the threads are thereby maintained under a proper tension at all times during the weaving operation.

85 One end of the shaft 19 of the primary feed and tension roll 17 has fixed thereto a pinion 20 which meshes with a gear 21 having an elongated sleeve 22 keyed or otherwise fixed to the adjacent end of the shaft 23 of the roll 18. Mounted to turn loosely on the hub of this gear 21 is a gear 24 of the same diameter as said gear 21 and having a hollow body open at its side facing the gear 21 and closed thereby. On the interior of the rim surface of the gear 24 is formed an annular series of ratchet teeth 25 adapted to engage a series of pivoted pawls 26 mounted upon pins or stub shafts 27 extending 90 from the outer face of the gear 21, which pawls are normally held in engagement with the ratchet teeth by springs 28.

95 The periphery of the rim of the gear 24 is formed with spur teeth meshing with a 100

pinion 29 on a stub shaft 30, which pinion is integral with a spur gear 31 rotating therewith on said shaft and driven by a worm 32 on the adjacent end of the driving shaft 2. As the pull of the warp threads is mainly on the roll 18 the roll 17 is positively connected therewith by the gears 20 and 21 in order to positively drive said roll 17 at a regulated speed with respect to the roll 18 and prevent slipping of said roll 17.

From the foregoing description, it will be understood that when the driving shaft 2 is in motion, the gears 29 and 31 will be directly driven therefrom, and the pinion 29 will transmit motion to the gear 24. This gear 24 regulates the let-off or feed motion of the gear 21 and the rollers 17 and 18, which gear 21 and rollers 17 and 18 are actuated for the let-off motion under the pull of the warp threads, which are drawn inwardly by the take-up rollers and the beating in mechanism. The shaft 2 rotating to the right or in the direction shown by the arrow in Fig. 1, turns the gear 29 and gear 31 to the left, whereby the gear 24 is driven in an inward direction or to the right at the proper rate of speed to regulate the let-off motion of the said gear 24 and rolls 17 and 18, according to the number of picks desired per inch of cloth. The ratchet teeth 25 of this gear 24 are of conventional construction, having beveled or inclined surfaces and abutting shoulders, which latter are, however, arranged at the forward ends of the beveled surfaces in the direction of motion of said gear. As the gear 24 rotates forwardly at a timed rate of speed, and the gear 21 and rollers 17 and 18 rotate under the pull of the threads, the teeth of the pawls 26 carried by the gear 21 engage the shoulders of the ratchet teeth of the gear 24, whereby the forward rotation of the gear 21, and consequently of the rollers 17 and 18, at a greater rate of speed than that of the gear 24 is prevented, whereby the excess feed of the warp threads by the let-off mechanism under the pull upon the warp threads from the take-up roller and beating mechanism is avoided. The feed of the warp threads will, accordingly, be regulated by the diameter and speed of rotation of the gear 24, and the pawl and ratchet connection between the same and the gear 21 acts in the nature of a clutch device, which prevents the forward rotation of the gear 21 at greater speed than the speed of rotation of gear 24 while permitting said gear 21 to be backed at any time to draw back the warp threads, the pawls 26 in the draw-back motion sliding over the inclined faces and shoulders of the ratchet teeth. The warp threads passing from the roll 15 will pass upwardly and rearwardly around the rolls 17 and then upwardly and forwardly around the roll 18, thereby insuring a proper feed action of said

threads, while maintaining them under a proper tension. By the use of interchangeable gears 24 of different sizes the feed of the warp threads may be regulated for any desired number of picks per inch of cloth. Through the clutch connection formed by the pawl and ratchet teeth of the gears 21 and 24, the gear 21 will be allowed under the pull of the warped threads to positively rotate forwardly with the gear 24 when the let-off mechanism is in operation, the engagement with the shoulders of the ratchet teeth preventing said gear 21 from turning at a greater rate of speed than said gear 24, while it also permits such gear 21 to be turned rearwardly when said mechanism is out of operation to enable the weaver to hold the warp threads back several inches at a time after picking out any amount of the threads to correct imperfections in the weaving operation. It will be observed that the crank 2^a and lever 12 are arranged at the front end of the loom frame, and, that by the arrangement of the clutch mechanism and drive gearing shown, the let-off mechanism may be thrown into and out of operation and the shaft 2 turned by the crank 2^a when the clutch is disconnected, to turn back the threads whenever desired, without the necessity of the operator going back to the rear end of the loom.

It will thus be seen that our invention provides a let-off mechanism which is simple and effective in construction, permits the warp threads to be readily pulled back for the purpose described, and insures a proper feed of the threads under the necessary tension at all times during the weaving operation without the necessity of employing auxiliary tensioning or take up means requiring manual manipulation. As a result, any imperfect tensioning of the threads, such as occur in the use of manually adjustable take up means, is avoided, thus preventing to a large extent liability of the breakage of the warps in the weaving process. While we have shown a certain means for transmitting power to the driving gear of the let-off mechanism from the loom driving mechanism, any other gearing suitable for the purpose may be employed.

We claim:—

1. In a let-off mechanism for looms, the combination of a loom driving mechanism including a main drive shaft, a warp roll having a let-off motion solely under the feed pull of the warp threads by the take-up and beating-in devices, primary and secondary guide rolls, intermeshing gears fixed to said guide rolls, a feed controlling gear loose on the shaft of the secondary guide roll alongside the gear thereon and provided with internal ratchet teeth, an auxiliary drive shaft in gear with said feed controlling gear for imparting a regulated and positive

feed motion thereto, means for throwing said auxiliary drive shaft into and out of gear with the main drive shaft, pawls carried by the gear on the secondary guide roll for cooperation with the ratchet teeth of the feed controlling gear, whereby the guide rolls and warp roll are adapted to rotate for a let-off action at a fixed speed controlled by the speed of said controlling gear and are coupled to said controlling gear for a reverse action to impart backward motion to the warp threads, and means for manually operating said auxiliary drive shaft for imparting backward motion to said guide rolls through the feed controlling gear when said auxiliary drive shaft is disconnected from the main drive shaft.

2. In a let-off mechanism for looms, the combination of a loom driving mechanism including a main drive shaft, a warp roll freely revoluble for a let-off motion solely under the feed pull of the warp threads by the take-up and beating-in devices, primary and secondary guide rolls, intermeshing gears fixed to said rolls, a feed controlling gear loose on the shaft of the secondary guide roll alongside of the gear thereon and provided with internal ratchet teeth, an auxiliary drive shaft having at one end a drive gear meshing with said feed controlling gear for imparting a positive feed

controlling motion thereto, spring actuated pawls on the gear of the secondary guide roll coöoperating with the internal ratchet teeth of the feed controlling gear to adapt said guide rolls and warp roll to have a let-off motion at a speed controlled by the speed of said feed controlling gear, and to adapt said guide rolls to be reversely turned for imparting a backward motion to the warp threads, an elongated hollow shaft inclosing a portion of the auxiliary drive shaft and in gear at one end with the main drive shaft, clutch mechanism at the take-up end of the loom for throwing said hollow shaft into and out of gear with the auxiliary drive shaft, and an operating handle upon the auxiliary drive shaft at the take-up end of the loom, whereby said auxiliary drive shaft, when thrown out of gear with the main drive shaft, may be turned in a reverse direction to transmit motion through the feed controlling gear to the guide rolls to feed the warp threads backwardly.

In testimony whereof we affix our signatures in the presence of two witnesses.
